(57) **ABSTRACT**

Replaceable blade knives have an elongated boss sized to closely receive an elongated aperture of the planar blade, a deflector element connected to the elongated body and operable to engage a rear end of the planar blade to deflect a selected portion of the blade defining a rear portion of the elongated aperture laterally between a retention position in which the selected portion engages the boss and a clear position in which the selected portion is clear of the rear portion of the boss, and a movable ejector element having a ejector surface adjacent to the rear edge of the blade and operable to eject the blade from the blade attachment facility in response to forward motion of the ejector element when the selected portion of the blade is in the clear position.

REPLACEABLE BLADE KNIFE**CROSS-REFERENCE TO RELATED APPLICATION**

This application is a Continuation-in-Part of U.S. patent application Ser. No. 17/961,242 filed on Oct. 6, 2022, entitled "REPLACEABLE BLADE KNIFE," which claims the benefit of U.S. Provisional Patent Application No. 63/287,107 filed on Dec. 8, 2021, entitled "REPLACEABLE BLADE KNIFE," which are hereby incorporated by reference in their entirety for all that is taught and disclosed therein.

FIELD OF THE INVENTION

The present invention relates to knives, and more particularly to a replaceable blade knife that restrains the blade in use while also reliably ejecting the blade in a safe manner.

BACKGROUND AND SUMMARY OF THE INVENTION

Hunting knives are a common tool for the outdoorsman. They are considered one of the most important items to be carried during any wilderness activity. To ensure ease of carry, the hunting knife should be as light as possible and no larger than is necessary to perform an intended task. For example, a hunting knife used for field dressing a deer, wild pig, or other animal to harvest meat must be sufficiently large while remaining light. The hunting knife must also remain sharp throughout the field dressing activity until harvesting is complete. This is where the size of knife and other factors, such as type of knife steel, contribute to the user's knife selection while pre-planning for these field activities.

A common problem occurs when, for a variety of reasons, the selected knife does not stay sharp even after thoughtful planning has occurred. Over the past several years, a solution to this problem has evolved where a knife handle that allows for a replaceable sharp blade has gained universal acceptance and popularity. Some common makers of these knives with replaceable blades are: Havalon Knives of Cincinnati, OH, Gerber Gear of Portland, OR, and Kershaw Knives of Tualatin, OR. Many of these relatively new knife products have been designed poorly with respect to overall size and weight, but have succeeded with high praise for their ability to provide a very inexpensive replacement blade in the field to assure a sharp edge regardless of extended heavy cutting activities. The user can replace a dull blade with a new sharp blade as needed until field activities are completed.

While many knife manufacturing companies have acknowledged this trend for products with replaceable blades, Havalon Knives has emerged as the clear leader in this product category. In fact, the word Havalon has become synonymous among users and retailers for this product almost universally. Another contributing element to this universally acknowledged term (Havalon), is that other knife makers have found it more convenient and economical to design and produce products using blades provided by Havalon Knives. These blades can be purchased from Havalon Knives in bulk volume very inexpensively, work very well, and are a proven product that the end user wants and recognizes.

However, some problems with replaceable blade knives have been identified by end users during normal use of these

knives. The most concerning is when the replaceable blade becomes unrestrained and slips out of the handle. This happens when the user is manipulating the knife with enough force to bend the rear of the blade high enough to achieve the proper elevation for removal of the blade. When this condition exists, a simple push of the blade or pull of the handle will cause the blade to disengage from the handle, often putting the user in danger of encountering a sharp edge and exposing them to cuts or potentially more serious injury. 5 A second problem occurs when the user has decided to replace a blade under field or other use conditions where their hands might be slippery because they are bloody or greasy. When this condition exists, it is difficult to lift the rear of the blade and push the lifted blade forward far enough to release the blade from the handle. This activity often results in the hand slipping from the grip of the blade and exposing the hand or fingers to the sharp edge of the blade and again exposing the user to potential injury. While other hazards exist, they are more or less similar to virtually 10 all other types of knives.

Replaceable blade knives are also used in the medical field, particularly in surgeries. Similar problems exist where medical personnel are exposed to undesirable risks of being injured because of inadvertent blade detachment or challenges with releasing the blade from the handle. There is also an additional risk of medical personnel being exposed to pathogens in the event they are cut by a used blade.

Therefore, a need exists for a new and improved replaceable blade knife that restrains the blade in use while also 15 reliably ejecting the blade in a safe manner. In this regard, the various embodiments of the present invention substantially fulfill at least some of these needs. In this respect, the replaceable blade knife according to the present invention substantially departs from the conventional concepts and 20 designs of the prior art, and in doing so provides an apparatus primarily developed for the purpose of restraining the blade in use while also reliably ejecting the blade in a safe manner.

The present invention provides an improved replaceable 25 blade knife, and overcomes the above-mentioned disadvantages and drawbacks of the prior art. As such, the general purpose of the present invention, which will be described subsequently in greater detail, is to provide an improved replaceable blade knife that has all the advantages of the 30 prior art mentioned above.

To attain this, the preferred embodiment of the present invention essentially comprises an elongated body having opposed ends, the elongated body having a handle portion extending to a handle end of the elongated body, and a blade attachment facility at an opposed forward end of the elongated body, the blade attachment facility having a blade support surface configured to abut a major face portion of the planar blade proximate the elongated aperture, an elongated boss sized to closely receive the elongated aperture of the planar blade, the elongated boss defining an undercut 35 configured to receive a blade portion at the constriction to prevent separation of the planar blade from the blade support surface when the planar blade is in an installed condition with the elongated boss received in the elongated aperture, 40 a deflector element connected to the elongated body and operable to engage the rear end of the planar blade to deflect a selected portion of the blade defining a rear portion of the elongated aperture laterally between a retention position in which the selected portion engages the boss and a clear 45 position in which the selected portion is clear of the rear portion of the boss, and a movable ejector element having a 50 ejector surface adjacent to the rear edge of the blade and

operable to eject the blade from the blade attachment facility in response to forward motion of the ejector element when the selected portion of the blade is in the clear position. There are, of course, additional features of the invention that will be described hereinafter and which will form the subject matter of the claims attached.

There has thus been outlined, rather broadly, the more important features of the invention in order that the detailed description thereof that follows may be better understood and in order that the present contribution to the art may be better appreciated.

BRIEF DESCRIPTION OF THE DRAWINGS

FIG. 1 is an isometric view of the current embodiment of a replaceable blade knife constructed in accordance with the principles of the present invention with the movable ejector element in the neutral position.

FIG. 2A is an exploded view of the replaceable blade knife of FIG. 1.

FIG. 2B is an enlarged exploded partial view of the replaceable blade knife of FIG. 1.

FIG. 3A is an enlarged isometric partial view of the movable ejector element and blade of FIG. 1 with the movable ejector element in the neutral position.

FIG. 3B is an enlarged bottom partial view of the movable ejector element and blade of FIG. 1 with the movable ejector element in the neutral position.

FIG. 4A is an enlarged side partial view of the replaceable blade knife of FIG. 1 with the movable ejector element in the neutral position.

FIG. 4B is an enlarged side partial view of the replaceable blade knife of FIG. 1 with the movable ejector element in the retracted position.

FIG. 4C is an enlarged side partial view of the replaceable blade knife of FIG. 1 with the movable ejector element in the extraction position.

FIG. 5A is a sectional view of the replaceable blade knife of FIG. 1 with the movable ejector element in the neutral position.

FIG. 5B is a sectional view of the replaceable blade knife of FIG. 1 with the movable ejector element in the retracted position.

FIG. 5C is a sectional view of the replaceable blade knife of FIG. 1 with the movable ejector element in the retracted position with the flexure element pressed to lift the blade.

FIG. 5D is a sectional view of the replaceable blade knife of FIG. 1 with the movable ejector element in the neutral position with the flexure element held and the blade resting on the ledge of the movable ejector element.

FIG. 5E is a sectional view of the replaceable blade knife of FIG. 1 with the movable ejector element in the extraction position with the blade having been ejected.

FIG. 6A is an enlarged isometric view of the replaceable blade knife of FIG. 1 with the movable ejector element in the neutral position.

FIG. 6B is an enlarged isometric view of the replaceable blade knife of FIG. 1 with the movable ejector element in the retracted position.

FIG. 6C is an enlarged isometric view of the replaceable blade knife of FIG. 1 with the movable ejector element in the retracted position with the flexure element pressed to lift the blade.

FIG. 6D is an enlarged isometric view of the replaceable blade knife of FIG. 1 with the movable ejector element

element in the neutral position with the flexure element held and the blade resting on the ledge of the movable ejector element.

FIG. 6E is an enlarged isometric view of the replaceable blade knife of FIG. 1 with the movable ejector element in the extraction position with the blade having been ejected.

FIG. 7 is a side view of the replaceable blade knife of FIG. 1 with the movable ejector element in the neutral position and dashed lines showing the blade in the ejection position.

FIG. 8 is a top isometric view of a first alternative embodiment of the replaceable blade knife constructed in accordance with the principles of the present invention with the movable ejector element in the neutral position.

FIG. 9 is an exploded view of the first alternative embodiment of the replaceable blade knife of FIG. 8.

FIG. 10 is an enlarged isometric partial view of the first alternative embodiment of the replaceable blade knife of FIG. 8 with the movable ejector element in the neutral position.

FIG. 11 is an enlarged isometric partial view of the first alternative embodiment of the replaceable blade knife taken along circle 11 of FIG. 8 with the movable ejector element in the neutral position.

FIG. 12 is an enlarged isometric partial view of the first alternative embodiment of the replaceable blade knife of FIG. 8 with the deflector element in the process of deflecting the blade in preparation for ejection.

FIG. 13 is an enlarged isometric partial view of the first alternative embodiment of the replaceable blade knife of FIG. 8 with the movable ejector element in the process of ejecting the blade.

FIG. 14 is an enlarged isometric partial view of the first alternative embodiment of the replaceable blade knife of FIG. 8 with the movable ejector element in the neutral position.

FIG. 15 is a top isometric view of a second alternative embodiment of the replaceable blade knife constructed in accordance with the principles of the present invention with the movable ejector element in the neutral position.

FIG. 16 is a top isometric view of the second alternative embodiment of the replaceable blade knife of FIG. 15 with the movable ejector element in the neutral position.

FIG. 17 is an exploded view of the second alternative embodiment of the replaceable blade knife of FIG. 15.

FIG. 18 is a bottom view of the second alternative embodiment of the replaceable blade knife of FIG. 15 with the movable ejector element in the neutral position.

FIG. 19 is a bottom view of the second alternative embodiment of the replaceable blade knife of FIG. 15 with the movable ejector element in the process of deflecting the blade in preparation for ejection.

FIG. 20 is a bottom view of the second alternative embodiment of the replaceable blade knife of FIG. 15 with the movable ejector element in the process of ejecting the blade.

FIG. 21 is an exploded view of a third alternative embodiment of the replaceable blade knife constructed in accordance with the principles of the present invention.

FIG. 22 is a top isometric view of the third alternative embodiment of the replaceable blade knife of FIG. 21 with the movable ejector element in the neutral position.

FIG. 23 is an enlarged isometric partial view of the third alternative embodiment of the replaceable blade knife of FIG. 21 with the movable ejector element in the neutral position.

FIG. 24 is an enlarged isometric partial view of the third alternative embodiment of the replaceable blade knife of FIG. 21 with the deflector element in the process of deflecting the blade in preparation for ejection.

FIG. 25 is an enlarged isometric partial view of the third alternative embodiment of the replaceable blade knife of FIG. 21 with the movable ejector element in the process of ejecting the blade.

FIG. 26 is an enlarged bottom sectional partial view of the third alternative embodiment of the replaceable blade knife of FIG. 21 with the movable ejector element in the neutral position.

FIG. 27 is an enlarged bottom sectional partial view of the third alternative embodiment of the replaceable blade knife of FIG. 21 with the deflector element in the process of deflecting the blade in preparation for ejection.

FIG. 28 is an enlarged bottom sectional partial view of the third alternative embodiment of the replaceable blade knife of FIG. 21 with the movable ejector element in the process of ejecting the blade.

FIG. 29 is an exploded view of a fourth alternative embodiment of the replaceable blade knife constructed in accordance with the principles of the present invention.

FIG. 30 is a left side view of the fourth alternative embodiment of the replaceable blade knife of FIG. 29 with the movable ejector element in the neutral position and the stop pin in the locked position.

FIG. 31 is a bottom sectional view of the fourth alternative embodiment of the replaceable blade knife of FIG. 29 with the movable ejector element in the neutral position and the stop pin in the locked position.

FIG. 32 is a bottom sectional view of the fourth alternative embodiment of the replaceable blade knife of FIG. 29 with the movable ejector element in the neutral position and the stop pin in the unlocked position.

FIG. 33 is a bottom sectional view of the fourth alternative embodiment of the replaceable blade knife of FIG. 29 with the movable ejector element in the process of deflecting the blade in preparation for ejection.

FIG. 34 is a bottom sectional view of the fourth alternative embodiment of the replaceable blade knife of FIG. 29 with the movable ejector element in the process of ejecting the blade.

FIG. 35 is a right side view of the fourth alternative embodiment of the replaceable blade knife of FIG. 29 with the movable ejector element in the neutral position and the stop pin in the locked position.

The same reference numerals refer to the same parts throughout the various figures.

DESCRIPTION OF THE CURRENT EMBODIMENT

An embodiment of the replaceable blade knife of the present invention is shown and generally designated by the reference numeral 10.

FIGS. 1-2B illustrate the improved replaceable blade knife 10 of the present invention. More particularly, the replaceable blade knife is a holder for a planar blade 12 having a forward end 14 and an opposed rear end 16, a sharp edge 18, and defining an elongated aperture 20 having a constriction at one end 22. The holder is an elongated body 24 having opposed ends. The elongated body has a handle portion 26 extending to a handle end 28 of the elongated body, and a blade attachment facility 30 at an opposed forward end 32 of the elongated body. The blade attachment facility has a blade support surface 34 configured to abut a

major face portion 60 of the planar blade proximate the elongated aperture. An elongated boss 36 is sized to closely receive the elongated aperture of the planar blade. The elongated boss defines an undercut 38 configured to receive a blade portion 40 at the constriction to prevent separation of the planar blade from the blade support surface when the planar blade is in an installed condition with the elongated boss received in the elongated aperture. A movable ejector element 42 formed by a sliding guard 64 and a sliding rear plate 66 is connected to the elongated body by flat head screws 68, 70. The moveable ejector element is operable to engage the rear end of the planar blade to eject the planar blade from the holder.

FIGS. 3A & B illustrate the improved movable ejector element 42 and planar blade 12 of the present invention. More particularly, the movable ejector element reciprocates along the length of the elongated body 24 forming the holder. The movable ejector element has a ledge 44 at a different level from the blade support surface 34 and configured to retain the rear end 16 of the planar blade 12 above the blade support surface. The distance between the different level and the blade support surface is adequate to elevate a portion of the planar blade at the rear end of the elongated aperture 20 above a rear end 46 of the elongated boss 36.

The movable ejector element 42 is movable between a first operational position shown in FIG. 4A in which the planar blade 12 is unflexed and abuts the blade support surface 34, a second position shown in FIG. 4B in which flexure of the rear end 16 of the planar blade away from the blade support surface is enabled, and a third position shown in FIG. 4C in which the movable ejector element is sufficiently forward of the first position to eject the planar blade from the holder.

The movable ejector element 42 includes a blade restraint 48 configured to prevent lateral deviation of the rear end 16 of the planar blade 12 when in the first operational position. In the current embodiment, the movable ejector element is biased toward the first operational position. This biasing is accomplished by a sloped surface 72 and detent 74 defined within a handle aperture 76 defined by the elongated body that interact with a wire form spring 62 protruding from a pocket 78 defined by the sliding guard 64. The movable ejector element has a forward-facing shoulder surface 50 configured to engage the rear end of the planar blade to enable ejection of the planar blade when the rear end of the planar blade is deviated sufficiently above the blade support surface 34. The ledge 44 is adjacent to the forward-facing shoulder surface. The movable ejector element is constrained by the planar blade against movement from the first operational position to the third position when the planar blade is against the blade support surface. The movable ejector element includes an external actuator 52 operably engaged by a user's finger. The external actuator is secured to the elongated body by a retaining ring 80. The movable ejector element has opposed grip surfaces 54, 56 on opposed sides of the holder. The movable ejector element is operable to slide in a direction parallel to the length of the holder. The movable ejector element is at an intermediate position along the length of the holder between the handle portion 26 and the blade attachment facility 30.

A flexure element 58, which extends from the button serving as the external actuator 52 in the current embodiment, is operable to flex the rear end 16 of the planar blade 12 away from the blade support surface 34. The movable ejector element 42 is movable between a first operational position in which the planar blade 12 is unflexed and abuts the blade support surface, a second position to the rear of the

first position in which flexure of the rear end of the planar blade away from the blade support surface is enabled, and wherein the flexure element is prevented by contact of the movable ejector element and the planar blade from flexing the planar blade when the movable ejector element is in the first position. The flexure element is connected to the movable ejector element. The flexure element is operated to move laterally with respect to the blade support surface.

The elongated boss 36 is a forward feature at the opposed forward end 32 of the elongated body 24 forming the holder. The elongated boss is partially grooved by the undercut 38 to provide a slightly snug holding feature for the planar blade 12. The slightly snug condition is achieved when the constriction at one end 22 of the elongated aperture 20 of the planar blade slides into the undercut on the elongated boss. To allow disengagement, the planar blade must be flexible enough to bend over the remainder of the elongated boss until full insertion of the constriction is achieved. At this point, the remainder of the elongated aperture is clear of the elongated boss, enabling the opposed rear end 16 of the planar blade to snap down and around the remainder of the elongated boss.

The planar blade 12 is now installed onto the elongated body 24 forming the holder. To remove the planar blade from the elongated body, the user lifts the opposed rear end 16 of the planar blade until the opposed rear end of the planar blade is clear of the elongated boss 36. The user then applies forward pressure to the planar blade so the constriction at one end 22 of the elongated aperture 20 of the planar blade slides out of the grooves on the elongated boss until the elongated aperture is free of the elongated boss. The user can then attach a replacement planar blade to the elongated boss in the manner described previously.

FIGS. 5A-6E illustrate the movable ejector element 42 in five staged positions arranged along the length of the elongated body 24 forming the holder. FIG. 7 illustrates the planar blade 12 in the installed condition on the elongated body in solid lines and in the ejected position in dashed lines. In FIGS. 5A & 6A, the movable ejector element is shown in the neutral position with the opposed rear end 16 of the planar blade 12 releasably secured by the blade restraint 48 and ready for use. In FIGS. 5B & 6B, the movable ejector element is shown in the retracted position in preparation for ejecting the planar blade. In FIGS. 5C & 6C, the movable ejector element is shown in the retracted position with the opposed rear end of the planar blade lifted for ejection by the flexure element 58. In FIGS. 5D & 6D, the movable ejector element is shown having returned to the neutral position with the opposed rear end of the planar blade resting on top of the ledge 44. In FIGS. 5E & 6E, the movable ejector element is shown in the forwardmost position ejecting the planar blade with the constriction at one end 22 of the elongated aperture 20 of the planar blade having slid out of the grooves on the elongated boss 36 in the process of being ejected.

In the neutral position, the blade restraint 48 of the movable ejector element 42 covers the opposed rear end 16 of the planar blade 12. This prevents the opposed rear end of the planar blade from lifting above the elongated boss 36, thereby preventing the blade from becoming dislodged from the elongated body 24 forming the holder. In the neutral position, the movable ejector element is biased forward of the retracted position by a wire form spring 62. The movable ejector element is obstructed from moving forward of the neutral position by the opposed rear end of the installed planar blade. Because the movable ejector element is spring-biased forward against the installed planar blade, the

replaceable blade knife 10 will perform much more reliably, and the user will be permitted to exert much more force in a variety of manipulations and cutting activities without dislodging the planar blade, than is possible with conventional replaceable blade knives.

The user must exert sufficient force to overcome the wire form spring 62 to move the movable ejector element 42 rearward to the retracted position to initiate ejection of the planar blade 12. The forward spring-bias exerted by the wire form spring makes it easy for the user to slide the movable ejector element 42 forward under the lifted opposed rear end 16 of the planar blade until the opposed rear end of the planar blade rests on the top of the ledge 44.

At this point, the movable ejector element 42 has returned to the neutral position. However, further forward movement of the movable ejector element is now possible because the opposed rear end 16 of the planar blade 12 no longer blocks the movable ejector element. As a result, the user can continue to push the movable ejector element forward, which pushes the planar blade forward and disengages the constriction at one end 22 of the elongated aperture 20 from the grooves on the elongated boss 36. Once the movable ejector element reaches the forwardmost position, the elongated aperture is completely disengaged from the elongated boss, and the planar blade is fully ejected from the elongated body 24 forming the holder.

It should be appreciated that the movable ejector element 42 and the flexure element 58 enable the user to lift the opposed rear end 16 of the planar blade 12 and subsequently push the planar blade 12 off the elongated boss 36 to eject the planar blade without having to directly contact the planar blade with their fingers. As a result, the blade ejection procedure is much safer for the user and easier to perform with fingers made slippery by blood or grease compared to conventional replaceable blade knives.

FIGS. 8-10 & 14 illustrate a first alternative embodiment of the improved replaceable blade knife 100 of the present invention. More particularly, the replaceable blade knife is a holder for a planar blade 12 having a forward end 14 and an opposed rear end 16, a sharp edge 18, and defining an elongated aperture 20 having a constriction at one end 22. The holder is an elongated body 124 having opposed ends. The elongated body has a handle portion 126 extending to a handle end 128 of the elongated body, and a blade attachment facility 130 at an opposed forward end 132 of the elongated body. The blade attachment facility has a blade support surface 134 configured to abut a major face portion 60 of the planar blade proximate the elongated aperture. An elongated boss 136 is sized to closely receive the elongated aperture of the planar blade. The elongated boss defines an undercut 138 configured to receive a blade portion 40 at the constriction to prevent separation of the planar blade from the blade support surface when the planar blade is in an installed condition with the elongated boss received in the elongated aperture. A movable ejector element 142 formed by a sliding guard 164 and a sliding rear plate 166 is connected to the elongated body by a flat head screw 168. A deflector element 170 is connected to the elongated body. The deflector element includes a ramp 180 in the current embodiment.

FIGS. 11-13 illustrate the first alternative embodiment of the improved replaceable blade knife 100 of the present invention. More particularly, FIGS. 11-13 depict how the deflector element 170 is operable to engage the rear end 16 of the planar blade 12 to deflect a selected portion of the planar blade defining a rear portion 182 of the elongated aperture laterally between a retention position shown in FIG.

11 in which the selected portion engages the elongated boss 136 and a clear position shown in FIG. 12 in which the selected portion is clear of the rear portion of the elongated boss. The moveable ejector element 142 is operable to engage the rear end of the planar blade to eject the planar blade from the holder, which is shown in FIG. 13.

It should be appreciated that the deflector element 170 is pivotally movable with respect to the movable ejector element 142 and pivotally connected to the movable ejector element. The deflector element pivots about a pivot axis 184 both perpendicular to the length of the elongated body 124 and parallel to a plane 186 defined by the planar blade 12. The movable ejector element 142 is movable along the length of the elongated body and is fixed with respect to the deflector element. At least one of the movable ejector element and the deflector element includes a retention hook 188 defining a hook channel 190 configured to receive an upper edge 192 of the planar blade and to prevent deflection of the planar blade. The retention hook is configured to be clear of the planar blade when the deflector element is moved to the clear position, which is shown in FIGS. 12 & 13.

FIGS. 15-17 illustrate a second alternative embodiment of the improved replaceable blade knife 200 of the present invention. More particularly, the replaceable blade knife is a holder for a planar blade 12 having a forward end 14 and an opposed rear end 16, a sharp edge 18, and defining an elongated aperture 20 having a constriction at one end 22. The holder is an elongated body 224 having opposed ends. The elongated body has a handle portion 226 extending to a handle end 228 of the elongated body, and a blade attachment facility 230 at an opposed forward end 232 of the elongated body. The blade attachment facility has a blade support surface 234 configured to abut a major face portion 60 of the planar blade proximate the elongated aperture. An elongated boss 236 is sized to closely receive the elongated aperture of the planar blade. The elongated boss defines an undercut 238 configured to receive a blade portion 40 at the constriction to prevent separation of the planar blade from the blade support surface when the planar blade is in an installed condition with the elongated boss received in the elongated aperture. A movable ejector element 242 formed by a sliding guard 264 is connected to the elongated body by a pin 292 received in a pin aperture 296. A pin slot 294 defined by the handle portion enables insertion of the pin into the pin aperture when the pin aperture is axially registered with the pin slot. A deflector element in the form of a pocket 290 is formed by the handle portion. The pocket receives the opposed rear end of the planar blade. A sliding rear plate 266 has a lateral protrusion 218 that is received in a slot 216 defined by the handle portion and is connected to a sliding lock element 288 by a flat head screw 268. The sliding lock element defines a pocket 298 to receive a rear end 280 of the sliding guard 264. The sliding lock element is biased forward by a spring 212 received in pocket 214 defined by the handle portion such that the pocket receives the rear end of the sliding guard unless a user applies sufficient force to overcome the spring to disengage the pocket from the rear end of the sliding guard. The sliding lock element prevents the sliding guard from pivoting about the pivot pin when the rear end of the sliding guard is received in the pocket.

FIGS. 18-20 illustrate the second alternative embodiment of the improved replaceable blade knife 200 of the present invention. More particularly, FIGS. 18-20 depict how the pocket 290 serving as a deflector element is operable to engage the rear end 16 of the planar blade 12 to deflect a

selected portion of the planar blade defining a rear portion 182 of the elongated aperture laterally between a retention position shown in FIG. 18 in which the selected portion engages the elongated boss 236 and a clear position shown in FIG. 19 in which the selected portion is clear of the rear portion of the elongated boss. The moveable ejector element 242 is operable to engage the rear end of the planar blade to eject the planar blade from the holder, which is shown in FIG. 20.

10 It should be appreciated that the pocket 290 serving as a deflector element is pivotally connected to the pivot pin 292. The pocket pivots about a pivot axis 284 both perpendicular to the length of the elongated body 224 and parallel to a plane 286 defined by the planar blade 12. The movable ejector element 242 is movable along the length of the elongated body and is fixed with respect to the deflector element. Engagement of the pocket 298 of the sliding lock element 288 with the rear end 280 of the sliding guard portion 264 of the movable ejection element prevents deflection of the planar blade. The rear end of the sliding guard portion is configured to be clear of the sliding lock element when the sliding lock element is moved rearwardly, thereby enabling the selected portion to be deflected to the clear position after pivoting the pocket serving as a deflector element, which is shown in FIGS. 19 & 20.

FIGS. 21 & 22 illustrate a third alternative embodiment of the improved replaceable blade knife 300 of the present invention. More particularly, the replaceable blade knife is a holder for a planar blade 12 having a forward end 14 and an opposed rear end 16, a sharp edge 18, and defining an elongated aperture 20 having a constriction at one end 22. The holder is an elongated body 324 having opposed ends. The elongated body has a handle portion 326 extending to a handle end 328 of the elongated body, and a blade attachment facility 330 at an opposed forward end 332 of the elongated body. The blade attachment facility has a blade support surface 334 configured to abut a major face portion 60 of the planar blade proximate the elongated aperture. An elongated boss 336 is sized to closely receive the elongated aperture of the planar blade. The elongated boss defines an undercut 338 configured to receive a blade portion 40 at the constriction to prevent separation of the planar blade from the blade support surface when the planar blade is in an installed condition with the elongated boss received in the elongated aperture. A movable ejector element 342 formed by a sliding guard 364 is connected to the elongated body by a pin 392 received in a pin aperture 396. A pin slot 394 defined by the handle portion enables insertion of the pin into the pin aperture when the pin aperture is axially registered with the pin slot. A deflector element 370 is formed by the movable ejector element. The deflector element includes a ramp 380 in the current embodiment.

FIGS. 23-28 illustrate the third alternative embodiment of the improved replaceable blade knife 300 of the present invention. More particularly, FIGS. 23-28 depict how the deflector element 370 is operable to engage the rear end 16 of the planar blade 12 to deflect a selected portion of the planar blade defining a rear portion 182 of the elongated aperture laterally between a retention position shown in FIGS. 23 & 26 in which the selected portion engages the elongated boss 336 and a clear position shown in FIGS. 24 & 27 in which the selected portion is clear of the rear portion of the elongated boss. The moveable ejector element 342 is operable to engage the rear end of the planar blade to eject the planar blade from the holder, which is shown in FIGS. 25 & 28.

It should be appreciated that the deflector element 370 is pivotally connected to the pivot pin 392. The deflector element pivots about a pivot axis 384 both perpendicular to the length of the elongated body 324 and parallel to a plane 386 defined by the planar blade 12. The movable ejector element 342 is movable along the length of the elongated body and is fixed with respect to the deflector element.

FIGS. 29, 30 & 35 illustrate a fourth alternative embodiment of the improved replaceable blade knife 400 of the present invention. More particularly, the replaceable blade knife is a holder for a planar blade 12 having a forward end 14 and an opposed rear end 16, a sharp edge 18, and defining an elongated aperture 20 having a constriction at one end 22. The holder is an elongated body 424 having opposed ends. The elongated body has a handle portion 426 extending to a handle end 428 of the elongated body, and a blade attachment facility 430 at an opposed forward end 432 of the elongated body. The blade attachment facility has a blade support surface 434 configured to abut a major face portion 60 of the planar blade proximate the elongated aperture. An elongated boss 436 is sized to closely receive the elongated aperture of the planar blade. The elongated boss defines an undercut 438 configured to receive a blade portion 40 at the constriction to prevent separation of the planar blade from the blade support surface when the planar blade is in an installed condition with the elongated boss received in the elongated aperture. A movable ejector element 442 is received in an elongated slot 464 defined by the elongated body. A stop pin 492 is received in a stop pin aperture 496 defined by the movable ejector element. A stop pin slot 494 defined by the handle portion enables insertion of the stop pin into the stop pin aperture when the stop pin aperture is axially registered with an enlarged rear end 440 of the stop pin slot. A deflector element 470 is formed by the movable ejector element. The deflector element includes a ledge 480 in the current embodiment.

FIGS. 31-34 illustrate the fourth alternative embodiment of the improved replaceable blade knife 400 of the present invention. More particularly, FIGS. 31-34 depict how the deflector element 470 is operable to engage the rear end 16 of the planar blade 12 to deflect a selected portion of the planar blade defining a rear portion 182 of the elongated aperture laterally between a retention position shown in FIGS. 31 & 32 in which the selected portion engages the elongated boss 436 and a clear position shown in FIGS. 33 & 34 in which the selected portion is clear of the rear portion of the elongated boss. The moveable ejector element 442 is operable to engage the rear end of the planar blade to eject the planar blade from the holder, which is shown in FIGS. 33 & 34. The position of the stop pin 492 determines if the moveable ejector element can slide forward within the elongated slot 464 defined by the elongated body 424. The stop pin secures the moveable ejector element in position in FIG. 31 and has been depressed inward in FIG. 32 to unlock the moveable ejector element. As the moveable ejector element is moved forward as is shown in FIG. 33, the deflector element deflects the planar blade to the clear position. As the moveable ejector element continues to move forward as is shown in FIG. 34, the ledge 480 engages the opposed rear end 16 of the planar blade to eject the planar blade from the blade attachment facility 430.

It should be appreciated that the fourth alternative embodiment includes a minimal number of parts so that once assembled, only the planar blade 12 can be separated from the finished assembly. The stop pin 492 is permanently pressed and peened (or welded) into the moveable ejector element 442 once the moveable ejector element has been

inserted into the elongated slot 464 defined by the elongated body 424. The assembled replaceable blade knife 400 is easily cleaned and sterilized, and no parts except for the planar blade can be disassembled accidentally or intentionally. Therefore, the fourth alternative embodiment is particularly attractive for medical use. The minimal number of parts also provides a reduced overall cost, which is particularly important for a potentially single use disposable item.

While current embodiments of a replaceable blade knife have been described in detail, it should be apparent that modifications and variations thereto are possible, all of which fall within the true spirit and scope of the invention. With respect to the above description then, it is to be realized that the optimum dimensional relationships for the parts of the invention, to include variations in size, materials, shape, form, function and manner of operation, assembly and use, are deemed readily apparent and obvious to one skilled in the art, and all equivalent relationships to those illustrated in the drawings and described in the specification are intended to be encompassed by the present invention.

Therefore, the foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention.

I claim:

1. A holder for a planar blade having a forward end and an opposed rear end, a sharp edge, and defining an elongated aperture having a constriction at one end, the holder comprising:

an elongated body having opposed ends; the elongated body having a handle portion extending to a handle end of the elongated body, and a blade attachment facility at an opposed forward end of the elongated body;

the blade attachment facility having a blade support surface configured to abut a major face portion of the planar blade proximate the elongated aperture; an elongated boss sized to closely receive the elongated aperture of the planar blade;

the elongated boss defining an undercut configured to receive a blade portion at the constriction to prevent separation of the planar blade from the blade support surface when the planar blade is in an installed condition with the elongated boss received in the elongated aperture;

a deflector element connected to the elongated body and operable to engage the rear end of the planar blade to deflect a selected portion of the blade defining a rear portion of the elongated aperture laterally between a retention position in which the selected portion engages the elongated boss and a clear position in which the selected portion is clear of the rear portion of the elongated boss; and

a moveable ejector element having a ejector surface adjacent to the rear edge of the blade and operable to eject the blade from the blade attachment facility in response to forward motion of the ejector element when the selected portion of the blade is in the clear position.

2. The holder of claim 1 wherein the deflector element is pivotally movable with respect to the moveable ejector element.

3. The holder of claim 2 wherein the deflector element pivots about a pivot axis perpendicular to the length of the elongated body.

4. The holder of claim 3 wherein the pivot axis is parallel to a plane defined by the planar blade.
5. The holder of claim 3 wherein the pivot axis is perpendicular to a plane defined by the planar blade.
6. The holder of claim 1 wherein the movable ejector element is movable along the length of the elongated body. 5
7. The holder of claim 6 wherein the deflector element is pivotally connected to the movable ejector element.
8. The holder of claim 1 wherein the movable ejector element is fixed with respect to the deflector element. 10
9. The holder of claim 1 wherein the deflector element includes a ramp.
10. The holder of claim 1 wherein at least one of the movable ejector element and the deflector element includes a retention hook defining a hook channel configured to receive an upper edge of the planar blade and to prevent deflection of the planar blade. 15
11. The holder of claim 10 wherein the retention hook is configured to be clear of the planar blade when the deflector element is moved to the clear position. 20
